UNITED STATES PATENT OFFICE.

JOHN WALDHEIM, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE

1,403,361.

Specification of Letters Patent. Patented Jan. 10, 1922.

Application filed February 19, 1920. Serial No. 359,931.

To all whom it may concern:

Be it known that I, JOHN WALDHEIM, a citizen of the United States, residing in Elizabeth, in the county of Union and State 5 of New Jersey, have invented certain new and useful Improvements in Combined Typewriting and Computing Machines, of which the following is a specification.

This invention relates to combined type-10 writing and computing machines, and especially to the kind known as the Underwood bookkeeping machine disclosed in the patent to Frederick A. Hart, No. 1,176,364, March 21, 1916, in which the numeral keys 15 set up digit-pins, the values of which are later carried into a totalizer. The digit-pins are usually mounted upon bars, one bar for each denomination; and as the typewriter carriage passes through a computing zone 20 these bars are brought into play, one at a time, by suitable denomination-selecting 25 mechanism. This comprises suitable linkages, one for each denominational bar, the linkages being engaged by selectors arranged on the typewriter carriage.

Since the carriage travels from right to left and the order of the computing bars is from left to right, there is usually provided in said machine a transposition mechanism, 30 whereby the computing bars may be rendered effective in their descending denominational order.

A feature of this invention is the provision of simplified and improved means comprising a single connection, common to all 35 of the computing bars, to serve both as transpositioning means and denominational selecting means; this being accomplished without effecting preliminary movements of the 40 computing bars.

To this end there is provided a sub-carriage to be moved by the typewriter carriage, to feed a set of intermediate pins over the indexing pins, and bring them into effective 45 relation with the pin-setting bars, so that the latter, when operated, may depress pins of equal value on the sub-carriage, and consequently depress the corresponding indexing pins on the denominational bars.

50 As the typewriter or main carriage passes from right to left through the computing zone, the sub-carriage is picked up to move rightwardly into effective relation with the computing bars. After the digit is typed in 55 the last denominational (units) position, the

pick-up mechanism is released from the carriage to permit the sub-carriage to be restored to its normal position.

Other features and advantages will hereinafter appear. 60

In the accompanying drawings,

Figure 1 is a sectional side elevation of the machine, showing the invention applied thereto.

Figure 2 is a perspective view of the sub- 65 carriage in its normal position.

Figure 3 is a vertical section through the sub-carriage, showing one of the spring-pressed pins thereon.

Figure 4 is a rear view of the machine. 70 some of the parts being broken away to show the interior structure.

Figure 5 is a fragmentary rear view, 75 showing the sub-carriage traveling over the computing bars.

In the Underwood bookkeeping machine, numeral keys 8 and alphabet keys 9, when depressed, operate key-levers 10 and 11, respectively, to rock bell-cranks 12 to swing type-bars 13 to cause the types 14 thereon to 80 print against the front side of a platen 15, rotatably mounted in a carriage 16. The carriage 16 travels on a front rail 17 and a rear rail 18 secured to the main frame 20, and is urged from right to left by a spring- 85 drum 21 connected to said carriage by a strap 22, so that the carriage may be fed at each type stroke, the type-bars being provided, for this purpose, with heels 23 to engage with a curved universal bar 24, to move 90 the latter rearwardly to vibrate a loose dog 25 and a fixed dog 26, on a pivoted dog-rocker 27, between teeth 28 of an escape- 95 ment wheel 30, having the usual one-way driving connection with a pinion 31 meshing with a feed rack 32 pivoted on the carriage.

The digits as they are typed in the various denominational positions, while the carriage passes through a computing zone, may 100 be set up on computing elements or bars 33 prior to running the numbers into the dial wheels 34 of a register 35, in a manner hereinafter described. To set up the digits, each numeral key-lever 10 has pivoted thereon a 105 plunger 36, which, as the key-lever is depressed, engages with an arm 37 on a shaft 38 to rock the latter; there being nine of these shafts, one for each numeral key. When one of the rock-shafts 38 is operated, 110

a corresponding one of a series of pin-setting elements or bars 40 is depressed in a manner clearly shown and described in the Hart patent herein referred to. The downward movement of the pin-setting bar 40 is effective, when the carriage 16 is in a computing zone, to set the corresponding one of a series of indexing devices or pins 41 on one of the computing bars, by means of 10 intermediate setting devices or pins 42 supported on a sub-carriage 43. The indexing pins on each computing bar have values from "1" to "9," inclusive, corresponding to the values of the setting bars 40. The sub-carriage 15 normally occupies the position, shown in Figures 2 and 4, with the row of intermediate setting pins to one side of the set of computing bars 33; said computing bars being arranged side by side in descending 20 denominational order from left to right (Figure 4). The sub-carriage occupies this position until the typewriter or main carriage 16 enters the computing zone, when the sub-carriage is picked up by means (hereinafter described) operated by the typewriter carriage, to cause said sub-carriage to travel step by step to bring the intermediate setting pins 42 into register with the indexing pins 41 on the various computing bars 33 in 25 denominational order for pin-setting operations, while the main carriage moves in the opposite direction through the computing zone.

The intermediate setting pins 42 may be 30 depressed by the setting bars 40 against return springs 44 (Figure 3) to set the indexing pins 41, the setting pins 42 being held in their normal ineffective position against a top plate 45, suitably secured to the sub-carriage.

The sub-carriage 43 moves back and forth on guide rails 46 and 47, and is provided with notches 48 and 49 to embrace said guide rails. It should be understood 45 that any other suitable form of guiding means may be used to guide said sub-carriage.

After the indexing pins corresponding to the digits of the number being typed have 50 been set on the various computing bars 33, the sub-carriage is released from the typewriter carriage, in a manner hereinafter described, to permit it to be restored to its normal position (Figure 4).

The set up number is then run into the 55 dial wheels 34 of the register. For this purpose, there may be provided an operating handle 50, which, when pulled forwardly, rocks a shaft 51, having two gear sectors 52 secured thereon, one at each end, to rotate pinions 53, each pinion meshing with a rack 54 of a general operator 55 to drive the latter forwardly. The general operator is provided with a cross-bar 56 to engage, as it 60 moves forwardly, the lower ends of the in-

dexing pins 41, which have been set in the path of its movement, to move the various computing bars forwardly through distances equal in values to the values of the set indexing pins; the computing bars being provided 70 at their forward ends with racks 57 meshing with pinions 58 suitably connected with the dial wheels 34, to rotate the latter relatively to a sight-opening 60, in a computer casing 61, through which the numbers on 75 the dial wheels may be read.

The usual tens-carrying mechanism, as shown in the above-mentioned Hart patent, may be provided for the dial wheels.

The computing bars 33 may be restored 80 to their normal positions by the cross-bar 56 of the general operator, after running the number into the dial wheels; said cross-bar engaging, for this purpose, on its return stroke, with lugs or projections 62 on the 85 computing bars.

The set-up pins may be restored, during the latter part of the return-stroke of the general operator, by a pin-restoring platform 59, which is moved upwardly toward 90 the computing bars 33 by the general operator, as in the Hart patent herein referred to.

To avoid unnecessary idle operations of the intermediate setting pins 42 on the sub-carriage or computer carriage 43, when the main carriage 16 is out of the computing zone, the pin-setting bars 40 may have cut-outs 63 to permit their depression without disturbing the intermediate setting pins.

The typewriter carriage may be rapidly 100 located in any selected denominational position of a column. For this purpose, there may be provided the usual decimal tabulator keys 64, which, when operated, depress levers 65 to raise plungers or counter-stops 66 105 into the path of column-stops 67 on a stop-bar 68, secured to the typewriter carriage; the stops 67 being adjustable to columnar positions of the carriage. The typewriter carriage is released when any one of the 110 counter-stops 66 is operated. This may be done in the usual manner by mechanism (not shown herein) which is effective to raise the feed rack 32 out of engagement with the escapement pinion 31, so that the carriage 115 may be pulled leftwardly by the spring-drum 21 until arrested by the column-stop 67 engaging the operated counter-stop 66.

The mechanism to pick up the sub-carriage 43, to cause it to travel over the computing bars when the main carriage 16 traverses a computing zone, may comprise a pick-up element or hook 70 to be engaged by the column-stops, one at a time, as the typewriter carriage enters the computing 125 zone. The pick-up hook may be pivotally connected at 71 to a lever 72 to swing the latter about its pivot 73 against the tension of a return spring 74. The lever 72 may be provided with a rack or gear sector 75 at 130

its lower end to rotate a gear wheel 76, secured to a shaft 77 supported by a bracket 78 fixed on a top plate 80 of the computer casing 61. The shaft 77 extends into the machine and is provided at its inner end with a gear wheel 81, meshing with a rack 82, secured to the sub-carriage 43, to move the latter to bring the intermediate setting pins 42 into register with the indexing pins 41 of the computing bars 33. As the pick-up hook advances with the typewriter carriage, it is guided by a pin 83 projecting therefrom and into a slot 84 in a fixed guide plate 85. The computer carriage 43 is released from the typewriter carriage when the latter passes out of the computing zone. To do this, the pin 83 on the pick-up hook engages with a cam 86 to move the pick-up hook 70 out of engagement with the column-stop or pick-up device 67, thus permitting the computer carriage 43 to be restored to its normal position (Figure 4) by the return spring 74.

The column-stops 67, set at columnar positions of the carriage in which no computation is to be performed, may be cut off at 87 (Figure 1) to clear the pick-up hook 70, so as to leave the computer carriage undisturbed when the typewriter carriage passes through a non-compute columnar position.

The column-stops 67 ride idly over the pick-up hook 70 when the typewriter carriage is returned to the beginning of a new line. For this purpose, the pick-up hook may be provided with a cam 88 to be engaged by the column-stops 67 to depress the pick-up hook against the tension of a spring 90 bearing against the pin 83 of said pick-up hook.

It will be seen that only one totalizer is shown, and when the machine is used for vertical or column-totalizing, only a single column or tabulator stop 67 is required to cause the computer carriage 43 to denominational select the computing bars.

If it is desired to effect horizontal or cross-computations in various columns, a tabulator stop effective to engage the pick-up hook 70 is set at each column in which computation is to be effected.

Variations may be resorted to within the scope of the invention, and portions of the improvements may be used without others.

Having thus described my invention, I claim:

1. In a combined typewriting and computing machine, the combination of a main carriage to traverse a computing zone, pick-up devices on said carriage, computing elements, indexing devices on said computing elements, numeral keys, key-operated setting elements, a sub-carriage, intermediate setting devices on said sub-carriage, and pick-up mechanism for said sub-carriage to be engaged by the pick-up devices, to cause the sub-carriage to move step by step with the main carriage.

main carriage to bring the intermediate setting devices into register with the indexing devices of the various computing elements and the setting elements as the main carriage traverses the computing zone. 70

2. In a combined typewriting and computing machine, the combination of a main carriage to traverse a computing zone, pick-up devices on said carriage, numeral keys, computing elements arranged side by side 75 in denominational order, each computing element having a set of indexing devices with values corresponding to the values of the numeral keys, key-operated setting devices, one for each numeral key, a sub-carriage, a set of intermediate setting devices having values corresponding to the values of said numeral keys, and mounted on said sub-carriage, pick-up mechanism for said sub-carriage to be engaged by said pick-up 80 devices, to cause said sub-carriage to move step by step with the main carriage to bring the intermediate setting devices into register with the indexing devices of the computing elements successively, in denominational 90 order, as the main carriage traverses the computing zone, and means to disengage the pick-up mechanism from the effective pick-up device as the main carriage passes out of the computing zone, to permit the restoration 95 of the sub-carriage.

3. In a combined typewriting and computing machine, the combination of a main carriage to traverse a computing zone, pick-up devices on said carriage, computing elements, indexing pins on said computing elements, numeral keys, pin setting bars operable by said numeral keys, a sub-carriage, intermediate setting pins on said sub-carriage, and pick-up mechanism for said sub-carriage to be engaged by the pick-up devices, to cause the sub-carriage to move step by step with the main carriage to bring the intermediate setting pins into register with the indexing pins of the various computing 100 elements one by one in their denominational order as the main carriage traverses the computing zone. 110

4. In a combined typewriting and computing machine, the combination of a main carriage to traverse a computing zone, pick-up devices on said carriage, numeral keys, computing elements, each computing element having a set of indexing devices with values corresponding to the values of the numeral keys, key-operated setting devices, a sub-carriage, a set of intermediate setting devices having values corresponding to the values of the numeral keys and mounted on said sub-carriage, the intermediate setting devices normally occupying a position to one side of the computing elements, said key-operated setting devices when operated being ineffective to operate the intermediate setting devices when the sub-carriage is in 120 130

its normal ineffective position, and pick-up mechanism for said sub-carriage to be engaged by said pick-up devices to cause said sub-carriage to move step by step with the 5 main carriage to bring the intermediate setting devices into effective relation with the key-operated setting devices, and into register with the indexing devices on the various computing elements successively in denominational order as the main carriage traverses 10 the computing zone.

5. In a combined typewriting and computing machine, the combination of a main carriage, pick-up devices on said carriage, 15 numeral keys, computing elements, each computing element having a set of indexing pins with values corresponding to the values of the numeral keys, key-operated setting bars having cut-outs, a sub-carriage, a set 20 of intermediate setting devices to be operated by said setting bars, said intermediate setting devices having values corresponding to the values of the numeral keys, and mounted on said sub-carriage, the 25 intermediate setting devices normally occupying a position to one side of the computing elements, and in register with the cut-outs of said setting bars, so that the setting bars, when operated while the sub-carriage is in 30 its normal ineffective position, are ineffective to operate said intermediate setting devices, and pick-up mechanism for said sub-carriage to be engaged by said pick-up devices to cause said sub-carriage to move step 35 by step with the main carriage to bring the intermediate setting devices into effective relation with the setting bars, and into register with the indexing pins on the various computing elements successively in denominational order as the main carriage traverses 40 the computing zone.

6. In a combined typewriting and computing machine, the combination of a main carriage, computing elements, indexing devices on said computing elements, key-operated setting devices, a sub-carriage, intermediate setting devices on said sub-carriage, said intermediate setting devices being normally out of effective relation with said key-operated setting devices, means whereby 45 said main carriage will move said sub-carriage to bring the intermediate setting devices into effective relation with the key-operated setting devices and into register 50 with the indexing devices of the computing elements successively, in denominational order, as the main carriage traverses the computing zone, so that an intermediate device 55 when actuated by a key-operated setting device will actuate an indexing device on the computing element of the denomination determined by the positions of the intermediate devices, and means to release said sub-carriage from said main carriage to permit 60 the restoration of said sub-carriage as the 65

main carriage passes out of the computing zone.

7. In a combined typewriting and computing machine, the combination of a main carriage to traverse a computing zone, pick-up devices, a normally ineffective computer carriage, pick-up mechanism including a pivoted lever, a pick-up element pivotally connected to said lever and to be engaged by the pick-up devices, an internal gear sector on the inner side of said lever, a pinion meshing with said rack, means operated by said pinion to cause the computer carriage to move step by step in accordance with the movement of the main carriage when the latter traverses the computing zone, and means to release said pick-up element from the pick-up devices to permit the restoration of said computer carriage when the main carriage passes out of the computing zone. 75

8. In a combined typewriting and computing machine, the combination of a main carriage to traverse a computing zone, pick-up devices on said carriage, a computer carriage, pick-up mechanism including a pivoted lever, a pick-up element associated with said lever to be engaged by the pick-up devices, a rack on said lever, a pinion meshing with said rack, means operated by said pinion to cause the computer carriage to move step by step in a direction opposite to that of the main carriage when the latter traverses the computing zone, and means to release said pick-up element from the pick-up devices to permit the restoration of said computer carriage when the main carriage passes out of the computing zone. 90

9. In a combined typewriting and computing machine, the combination of a main carriage to traverse a computing zone, pick-up devices on said carriage, a normally ineffective computer carriage, pick-up mechanism comprising a pivoted lever, a pick-up hook on said lever to be engaged by said pick-up devices, an internal gear sector on the inner side of said pivoted lever, a pinion meshing with said sector, a second pinion connected with the first-mentioned pinion, a rack on said computer carriage with which said second pinion meshes, to move the computer carriage step by step in accordance with the movement of the main carriage when the latter traverses the computing zone, and means to release said pick-up mechanism from the main carriage when the latter passes out of the computing zone. 105

10. In a combined typewriting and computing machine, the combination of a main carriage to traverse a computing zone, pick-up devices on said carriage, computing elements, indexing devices on said computing elements, numeral keys, key-operated setting devices, a sub-carriage, intermediate setting devices on said sub-carriage, a piv- 110

125

130

oted lever, a pick-up element connected to said lever, and to be engaged by the pick-up devices, a rack on said lever, a pinion meshing with said rack, and means operated by 5 said pinion to cause the sub-carriage to be moved step by step to bring the intermediate setting devices into register with the indexing devices of the various computing elements as the main carriage traverses the 10 computing zone.

11. In a combined typewriting and computing machine, the combination of a main carriage to traverse a computing zone, pick-up devices on said carriage, numeral keys, 15 computing elements arranged side by side, in denominational order, each computing element having a set of indexing devices, with values corresponding to the values of the numeral keys, key-operated setting devices, one for each numeral key, a sub-carriage, a set of intermediate setting devices having values corresponding to the values of said numeral keys, the set of intermediate setting devices being supported on said 20 sub-carriage, a pivoted lever, a pick-up element connected to said lever, and to be engaged by the pick-up devices, a rack on said pivoted lever, a pinion meshing with said rack, means operated by 25 said pinion to cause the sub-carriage to move step by step with the main carriage, to bring the intermediate setting devices into register with the indexing devices on the computing elements successively, in denominational order, 30 as the main carriage traverses the computing zone, and means to disengage the pick-up element from the effective pick-up device as the main carriage passes out of the computing zone to permit the restoration of 35 the sub-carriage.

12. In a combined typewriting and computing machine, the combination of a carriage to traverse a computing zone, numeral keys, computing elements arranged side by side and in denominational order, indexing devices on said computing elements, setting elements associated with the numeral keys, 45 denomination-selecting mechanism comprising a series of intermediate setting devices, means to connect said denomination-selecting mechanism with said carriage as the latter enters the computing zone, so that the intermediate setting devices may be 50 moved step by step in accordance with the

movement of the typewriter carriage, into 55 register with the indexing devices on said computing elements, and means to release said denomination-selecting mechanism from said carriage as the latter passes out of the computing zone. 60

13. In a combined typewriting and computing machine, the combination of a carriage to traverse computing zones, numeral keys, computing elements arranged side by side in denominational order, a series of indexing devices on each of said computing elements, setting elements associated with said numeral keys, a traveling support, a series of intermediate setting devices on said support, and means to render said intermediate setting devices effective to be engaged by said setting elements and to cause said support to travel step by step in accordance with the movement of said carriage as the latter passes through computing 75 zones at various intervals in its travel, to successively bring the intermediate setting devices into register with the indexing devices on each of the computing elements in denominational order. 80

14. In a combined typewriting and computing machine, the combination of a carriage to traverse a computing zone, numeral keys, computing elements, a set of indexing devices on each computing element, each set 85 of indexing devices having values corresponding to the numeral keys, setting elements actuatable by said numeral keys to set said indexing devices, denomination-selecting means to travel between said setting elements and said indexing devices, means comprising a substantially vertically-disposed lever to be operated by said carriage when the latter traverses the computing zone, horizontally-disposed means connecting said denomination-selecting means with said vertically-disposed lever, and means on said carriage to operate said lever to cause said denomination-selecting means to move step by step into effective relation with the 90 various computing elements in denominational order, so that the indexing devices on the various computing elements may be set by said setting elements. 95
